DESIGN FOR A MOLDED FRAME FOR PICTURES AND LIKE ARTICLES

John H. Scott, Jr., Rockville Centre, and Wallace
J. Hardgrove, Jr., Freeport, N. Y.

Application February 26, 1941, Serial No. 99,220

Term of patent 7 years

To all whom it may concern:

Be it known that we, John H. Scott, Jr., and Wallace J. Hardgrove, Jr., citizens of the United States and residents of Rockville Centre, Nassau County, State of New York, and Freeport, Nassau County, State of New York, respectively, have invented a new, original, and ornamental Design for Molded Frames for Pictures and Like Articles, of which the following is a specification, reference being had to the accompanying drawings, forming part thereof.

In the drawings accompanying this specification—

Fig. 1 is a front view of a picture frame showing our design;

Fig. 2 is a rear view thereof; and

Fig. 3 is a sectional view on line 3—3 of Fig. 2.

We claim:

The ornamental design for a molded frame for pictures and like articles, as shown.
